UNITED STATES PATENT OFFICE.

AARON H. PARKER, OF BOSTON, MASSACHUSETTS.

DENTAL PLATE.

SPECIFICATION forming part of Letters Patent No. 317,667, dated May 12, 1885.

Application filed April 9, 1884. (No model.)

To all whom it may concern:

Be it known that I, AARON H. PARKER, of Boston, Massachusetts, a citizen of the United States, have invented certain new and useful 5 Improvements in Dental Plates, of which the following is a specification.

My invention relates to improvements in the construction of dental plates adapted to be secured in place within the mouth of the 10 wearer by atmospheric pressure; and it has for its object to obtain a more firm and rigid fitting and holding of such plates than have heretofore been accomplished.

In the accompanying drawings is represented 15 a dental plate in which my present improvement is embodied in the form now best known to me.

Figures 1 and 2 are views in plan of the upper and lower sides of said plate, respectively. 20 Fig. 3 is a vertical section through said plate on the line *xx* of Fig. 1, and Fig. 4 a section of a part of Fig. 3, illustrative of its construction and operation, both these figures being upon an enlarged scale as compared with Figs. 1 25 and 2.

My present improvement consists, in part, in forming a passage through the plate, whereby the air between it and the mouth may be exhausted more readily and completely, and 30 the plate thereby fitted more firmly and securely than could heretofore be done. In connection with this passage I provide a valve to prevent the re-entrance of air from outside under atmospheric pressure.

In addition to the vacuum chamber or depression A, I may also add to it auxiliary 35 chambers or depressions B B, preferably located upon the rear lateral parts of the plate under the extremities of the alveolar processes, as shown. These auxiliary chambers, which I believe to be new with myself, are preferably made to connect or communicate with the main chamber A, so that the exhausting, sucking, or drawing out of the air 40 through the one valved passage will exhaust the air from all the chambers A B B. It is obvious that a valved air-exhaust may be applied directly to each supplementary chamber, although the construction shown in Fig. 1 is 45 preferred by me.

The relative location of the vacuum-chambers A B B, which form the points of strongest adhesion of the plate, should be substantially as shown, the main or central chamber, A, covering the central palatal surface of the 55 plate, and the subsidiary chambers, B B, being located in the base or rearward lateral extremities or heel-pieces, as shown. The collective area of these three chambers may be as large as their location upon the plate will permit, 60 so long as enough of the true surface or base of the plate is left to give a good bearing against the mouth and prevent pain and discomfort to the wearer.

When the air-passage *a* is formed in a plate 65 provided with a single vacuum-chamber, it should connect with said chamber; when a series of vacuum-chambers is used, I prefer to carry the air-passage from the main or central chamber of the series. 70

The valving of the air-exhaust passage *a* may be done in any desired manner which will permit the air to be drawn out and prevent its return.

I have shown in Figs. 2, 3, and 4 a convenient method of forming the valve and attaching it in its place. The valve represented in these figures I make of a disk of kid or similar suitable packing material, (shown at *b*), over which is placed a retaining-plate, *c*, formed 75 of the same material as the dental plate itself, commonly hard rubber, and this is kept in place by the button *d*, Fig. 2. The seating for the plates *b* and *c*, I ordinarily form in the plate itself, as shown in the drawings. 80

I claim—

1. The combination, substantially as set forth, of the plate, the main vacuum-chamber, the supplemental chambers, the connecting-passages between the main chamber and 90 the supplemental chambers, and the valve which permits the passage of air from the several chambers.

2. The combination, substantially as set forth, of the plate, the vacuum-chamber, the 95 air-passage *a*, and the valve that normally closes the air-passage and that is sunk into the plate so as to present a plane surface to the interior of the mouth.

3. In an atmospheric dental plate, the com- 100

bination of the main vacuum-chamber A, the supplemental chambers B B, passages for connecting the chambers, the air-exhaust *a*, valve *b*, plate *c*, and retaining device *d*, said 5 valve, plate, and retaining device being sunk below the surface of the plate, substantially as set forth.

In testimony whereof I have hereunto subscribed my name this 7th day of April, A. D. 1884.

AARON H. PARKER.
